COKING CHAMBER

Leonard W. Robbie, Chicago, Ill., assignor to
 Universal Oil Products Company, Chicago, Ill.,
 a corporation of Delaware

Application August 15, 1940, Serial No. 352,735

3 Claims. (Cl. 202—266)

This invention particularly relates to an improved form of vessel or receptacle of the type in which hydrocarbonaceous materials such as petroleum oil, coal, peat, lignite, oil shale, asphalt, pitch, resin and the like or mixtures of such materials are distilled to substantial dryness and wherein the resulting substantially solid carbonaceous residue or coke is allowed to accumulate during the distilling operation and subsequently removed from the vessel.

Coking chambers of this general type are widely utilized in conjunction with or as an integral part of cracking units and, due to the capital investment represented, as well as the demand for cracked gasoline, it is of primary importance to operate the cracking unit as continuously as possible with a minimum of non-productive time for cleaning out the equipment and preparing it for further operation. It is common practice to employ a plurality of alternately operated coking chambers, one or more of which are cleaned and prepared for further operation, while the coking operation is continued in another or others of the group. This practice makes possible much more prolonged periods of operation between shut-downs and the use of a plurality of coking chambers of sufficient individual capacity, in conjunction with modern methods of coke removal, eliminate coking as the "bottle neck" in a continuous cracking and coking operation. However, the coking step is still an item of considerable expense, due not only to the cost of the coking equipment itself, but also to the cost of modern coke removal equipment and the labor involved in its operation.

The improved form of coking chamber herein provided materially simplifies and expedites coke removal and materially reduces the cost of coke removal equipment, as compared with that required when conventional coking chambers are employed.

This improved form of chamber departs from the conventional cylindrical coking chamber with top and bottom man-ways of reduced diameter in relation to that of the chamber, in that it is progressively larger in diameter from top to bottom, resembling a truncated cone in shape, and having a removable lower head which, when removed, leaves a bottom opening in the chamber which is the full area of the chamber at its point of greatest diameter.

With this form of vessel, substantially the entire mass of coke accumulated in the chamber may be pulled or dropped through the bottom

opening and, to facilitate this, when required, I provide an interior structure which is placed or hung within the chamber before it is headed-up and placed in operation. This interior structure comprises a plurality of vertically spaced horizontal perforate or open-work partitions which are united by cables, rods or the like and become enmeshed with the coke mass deposited in the chamber. By pulling the free lower end 5 of a cable, chain or the like attached to the structure, the entire mass of coke is loosened from the sloping chamber walls and falls through the lower opening. Thus, in most instances, except for a small amount of scaling-down or hand-cleaning sometimes required about the inlet and outlet connections and upper man-way and cleaning of the lower head, the entire vessel is cleaned in a single simple and rapidly accomplished operation and may be immediately headed up and conditioned for further service by purging, preheating and the like, as required.

Although a full diameter removable lower head involves the use of heavy flanges and bolting and is an item of greater expense than a 10 small diameter lower man-way such as employed in conventional coking chambers and makes a vessel of the improved form herein provided more expensive to construct than a conventional coking chamber of equal size, this additional expense is largely nullified and in many instances more than compensated for by the use of smaller coking chambers. This is possible when the improved form of chamber herein provided is employed, since clean-out time is materially reduced. This permits shortening of the operating cycle, with respect to the individual chambers, by a corresponding amount and thus reduces the required capacity of each individual chamber. As an alternative, in installations 15 which would require three or more conventional coking chambers of a given capacity, one or more may be eliminated, when chambers of the improved form and of equal individual capacity are employed, due to the shortening of the clean-out time required with the improved form of chamber and the improved means of coke removal provided.

The accompanying diagrammatic drawing illustrates the improved form of chamber provided by the invention, including one specific form of apparatus for facilitating the removal of coke therefrom.

Fig. 1 is a cross-sectional elevation of the chamber with the removable lower head in place and with a suspended interior structure which serves

55

to facilitate removal of the coke mass as a unit.

Fig. 2 is a plan view of one of the open-work members of the suspended interior structure.

Fig. 3 is an enlarged detail, shown partially in section, of the suspending mechanism designated by the reference numeral 17 in Fig. 1, and;

Fig. 4 is a plan view of the apparatus shown in Fig. 3.

Referring now particularly to Fig. 1, the sloping walls designated by the reference numeral 1, terminate in an upper elliptical head 2 and a lower flange 3. Preferably, the truncated conical shell 1 is made up of a plurality of rolled steel rings welded along their vertical and horizontal seams in the approved conventional manner with the welding beads on the interior of the vessel ground substantially flush with the walls, to eliminate protrusions which would interfere with the removal of the coke mass in the manner provided and hereinafter described.

It will be noted with reference to the drawing that the walls 1 of the vessel flare slightly outward from top to bottom and, preferably, the interior diameter of the vessel increases uniformly from the top downward to substantially the face of the lower flange 3. This lower flange is also preferably welded to the shell 1 and the upper head 2 is also preferably welded to the shell.

The upper head 2 is provided, in the case here illustrated, with a central flanged man-way nozzle 4 and a companion blind flange or cover plate 5 bolted to the flange of the man-way nozzle, as indicated, and preferably a gasket or suitable ground joint facing of any desired conventional form, not illustrated, is provided between the flanges to maintain a tight joint and prevent leakage. A flanged inlet nozzle connection 6 and a flanged outlet nozzle connection 7 is also provided in the upper head 2, in the case here illustrated.

The lower flanged head 8 of the vessel is releasably secured to flange 3 by bolts 9 and the flanges are suitably faced to accommodate a gasket 10 or to provide any conventional form of ground joint facing therebetween to maintain a tight joint and prevent leakage. A flanged nozzle connection 11 is provided centrally in the lower head 8, in the particular case here illustrated. This nozzle 11 may serve as a drain line connection and/or as a means of introducing steam, water or other suitable cooling material into the mass of coke accumulated in the chamber before the lower head is removed, to purge the chamber of hydrocarbon vapors and gases, hasten cooling and shorten the clean-out period.

When the weight of the mass of coke accumulated within the chamber is sufficient to overcome the adhesive tendencies between the outer surface of the coke mass and the relatively smooth interior walls of the chamber, the coke mass will, in the absence of means for preventing such action, fall from the chamber when the lower head 8 is removed. This will ordinarily occur when relatively dense hard coke is formed and rupture of the bond between the coke mass and the chamber walls is often accomplished or facilitated by shrinkage of the coke mass which occurs when it is cooled by the introduction of steam, water or the like, as above mentioned. On the other hand, with some types of coke an application of external force is required to free the mass from the walls of the vessel, but, by virtue of the sloping walls and the elimination of obstructions therefrom, friction between the chamber walls

and the moving mass of coke is substantially eliminated and, once the bond is broken between the chamber walls and the coke mass, the latter will fall through the lower opening.

To obviate hazard and eliminate the possibility of unintentional dropping of the coke mass before the lower head is completely removed and the workmen have retreated to a point of safety, the invention provides means for retaining the coke mass in the chamber after the lower head is removed therefrom until its removal is desired. The same means may also be employed, when required, for imparting the initial externally applied force to the coke mass to free it from the chamber walls. In the particular case here illustrated, the coke-supporting and disengaging means comprise a plurality of vertically spaced web-like members 12 of which Fig. 2 is a typical plan view. Each of these members comprises 10 radial rods or bars 13 each secured to a plurality of circular metal hoops or rings 14. Each of the members 12 extend substantially across the diameter of the portion of the chamber in which they are located and they are spaced and held together by members 15 which may be rods or, preferably, are flexible members such as a chain, wire cable or the like. The members 15 are united above the uppermost member 12 and terminate in a suitable loop or the like 16 by means of which the assembly is suspended within the chamber from member 17 located within the upper man-way nozzle. The members 15 are likewise united beneath the lowermost member 12 and terminate in a suitable loop or the like 18 attached to a hook 19 on the removable lower head of the vessel.

As coke is deposited and built up within the chamber, the members 12 become embedded therein but their form is such that they offer no appreciable resistance to the flow of fluids entering and leaving the chamber nor to the revolution of vapors and gases from the mass of semi-solid material undergoing coking. The members 12 and 15 serve to unite the entire mass of coke which is finally deposited within the chamber so that it may be removed therefrom substantially as a unit and, preferably, these members are of sufficient size and strength to support the coke bed, when necessary, and prevent its unintentional dropping when the bottom head is removed.

Referring now particularly to Figs. 3 and 4, member 17 comprises a pair of brackets 20 welded or otherwise firmly attached to the neck of man-way nozzle 4 and an arm 21 hinged to the brackets by means of pin 22 and terminating at the opposite end in a hook 23. A metal ring or the like 24, adapted to pass around the protruding corners 25 of brackets 20, serves to retain arm 21 in a substantially horizontal position to support the assembly comprising members 12 and 15, except when it is desired to remove the coke mass from the chamber, the ring 24 being adapted to slip over the ends 25 of brackets 20 toward the hooked end of member 21, allowing the latter to drop and release loop 16 (see Fig. 1) when it is desired to remove the coke mass.

In cleaning the chamber after it has been isolated from the rest of the system, substantially purged of vapors and gases and sufficiently cooled, the lower head 8 and the upper cover plate 5 are removed, loop 18 is then detached from hook 19 and, when required, is secured to a cable on the drum of a suitable power operated winch or the like, not illustrated, during which

time unintentional dropping of the coke mass is prevented by leaving the upper end of members 15 attached to the supporting mechanism 17. Then, when everything is in readiness for dropping the coke mass from the chamber, with the area beneath the chamber cleared and workmen out of the way, ring 24 is driven from the supporting brackets 20 of member 17, allowing arm 21 to drop and release the loop 16 at the upper end of members 12 from hook 23. If the coke mass then does not drop from the chamber by its own weight, power is applied to the winch and transmitted through members 15 and 12 to the entire mass of coke which is thus freed from the chamber walls and drops out of the chamber. Preferably, the winch is located a considerable distance from the chamber so that the assembly comprising members 12 and 15 and the coke which adheres thereto may be dragged from beneath the chamber to a convenient location at which said adhering coke is removed. Preferably, to avoid delay a duplicate assembly of members 12 and 15 is provided which is ready to be hung within the chamber as soon as the coke mass is dropped therefrom and any required incidental cleaning of the nozzles and the like is accomplished. The chamber may thus be heated up and prepared for further operation within a short time (normally approximately 30 minutes and often less) after it is opened for cleaning.

I claim as my invention:

1. A vessel of the class described comprising, in combination, a substantially vertical, substantially cylindrical metal shell normally closed at its upper end and of progressively increasing internal diameter from its upper to its lower end, the interior surface of the sloping walls of the shell being substantially smooth and free of obstructions and said walls terminating at their point of greatest diameter, a metal head spanning the entire diameter of the shell at its lowermost point and releasably secured to the shell, and a plurality of rigid perforate supporting members disposed at vertically spaced elevations within said shell and releasably suspended from the upper end of the vessel by means accessible through an opening therein provided with a removable cover plate, each of said web-like mem-

bers progressively increasing in diameter from the upper end of said shell to the lower end thereof.

2. A vessel of the class described comprising, in combination, a substantially cylindrical metal shell normally closed at its upper end and of progressively increasing internal diameter from its upper to its lower end, and open at its point of greatest diameter, the interior surface of the sloping walls of the shell being substantially smooth and free of obstructions, a metal head spanning the entire diameter of the shell at its lower end and releasably secured to the shell, and a plurality of openwork, substantially disc-shaped members progressively increasing in diameter from top to bottom of the said shell disposed at vertically spaced elevations within said shell and releasably suspended from the upper end of the vessel by means accessible through an opening therein provided with a removable cover plate.

3. A vessel of the class described comprising, in combination, a metal shell of substantially truncated conical shape internally, said metal shell having an integral upper head provided with a manway nozzle and removable cover plate therefor, said shell being of progressively increasing interior diameter from its upper to its lower end and open at said lower end, the interior surface of the sloping walls of the shell being substantially smooth and free of obstructions, a metal head spanning the entire diameter of the shell at its lower end and removably secured to the shell, suspension means comprising a hinged hook adapted to be fixed in operative and released to inoperative position, said hook being secured to the vessel adjacent the upper end of the vessel and accessible upon removal of the cover plate from said manway nozzle, a flexible hanger member suspended at its upper end from said hook and adapted to be releasably secured at its lower end to the removable lower head of the vessel, and a plurality of open-work, disc-like members disposed at spaced vertical elevations within said shell and supported by said hanger member.
